CLAIM

The ornamental design for a salad maker, as shown and described.

DESCRIPTION

FIG. 1 is a front, right side, top perspective view of the salad maker showing my new design;
FIG. 2 is a rear, right side, bottom perspective view thereof;
FIG. 3 is a top plan view thereof;
FIG. 4 is a bottom plan view thereof;
FIG. 5 is a right side elevational view thereof;
FIG. 6 is a left side elevational view thereof;
FIG. 7 is a front elevational view thereof;
FIG. 8 is a rear elevational view thereof; and,
FIG. 9 is a front, right side, usage perspective view thereof. The broken lines are for illustrative purposes only and form no part of the claimed design.
